UNITED STATES PATENT OFFICE.

WILLIAM A. MEYERS, OF CHICAGO, ILLINOIS.

HAIR WAVER.

Application filed December 17, 1923. Serial No. 681,034.

To all whom it may concern:

Be it known that I, WILLIAM A. MEYERS, a citizen of the United States, residing at Chicago, in the county of Cook and State of Illinois, have invented new and useful Improvements in Hair Wavers, of which the following is a full, clear, concise, and exact description, reference being had to the accompanying drawing, forming a part of this specification.

My invention relates to hair waving devices and more particularly to an improved device of this type, which is extremely simple to operate and efficient in imparting an artistic wave to the hair.

Heretofore in the art, hair waving devices have been either difficult to operate, or complicated in construction and therefore expensive to make. However, certain other devices of this type have been known and have become quite popular on the market, but, for obvious reasons, do not impart a wave to the hair as quickly or permanently as may be desired.

It is an object of my invention to provide an improved hair waver, which will overcome the above objections, by being simple in operation, as well as in design, so that the same may be manufactured and marketed at a minimum price, and yet afford a device exceedingly efficient and capable of imparting a wave to the hair which will remain therein a reasonable time.

According to the teachings of my invention, a plurality of U-shaped members are foldably connected, side by side, to provide a series of transverse hair engaging portions. These members are adapted to be folded together to allow a strand of hair to pass through the centers thereof, whereupon they are again extended and folded in a reversed direction. This novel folding relation of the U-shaped members permits the latter to crimp the hair upon the reversed fold in a very unique manner, and further permits a suitable pressure to be applied so that the waves in the hair will be of a permanent nature and remain in the hair a maximum time.

As a further object of my invention, I provide a compression element carried upon the device for applying this pressure to the hair. An elastic strap looped transversely across one of the U-shaped members and in a position to extend circumferentially around

all the U-shaped members in reversed folded position upon the hair may be used for this purpose. It will, however, later appear that any similar form of compression element may be used instead.

In order to apprise those skilled in the art how to construct and practice my invention, I shall now describe an embodiment thereof in connection with the accompanying drawings, which form a part hereof:

In the drawings:

Figure 1 is a top plan view of a hair waver embodying my invention, illustrating the device in extended position;

Fig. 2 is a side elevation of the same;

Fig. 3 is a side view of the device in its first folded position, illustrating the manner of placing the device upon the hair;

Fig. 4 illustrates the manner of extending or opening the device upon the hair after the hair has been inserted in the manner shown in Fig. 3;

Fig. 5 is a side view of the device in reversed, folded position, with the strands of hair passing over the various transverse hair engaging portions thereof so that the hair is crimped and held in this condition until waved; and,

Fig. 6 is a view similar to Fig. 1, only on a smaller scale, illustrating a modified form of my device.

The embodiment which I have chosen to illustrate my invention comprises a plurality of U-shaped members 1 to 9 inclusive, which are arranged side by side and foldably connected together. The particular number of these members employed is immaterial, it depending, of course, upon the size of the strand of hair to be waved. These members are provided with transverse hair engaging portions 10, and are preferably of U-shape formation with their free ends pivotally connected at 11 to the corners of the U of the adjoining member. When the members are thus connected together, central openings 12 are formed therebetween, and, as I shall presently describe, these openings 12 are made to align with each other when the members are folded so that hair may pass therethrough.

The end member 1 is preferably of different formation, and has its ends bent around at 13 to form loops 14 for receiving the pivotal connections 11 of the adjoining member 2. The central part of member 1,

however, is also provided with a transverse hair engaging portion the same as the rest of these members.

It will be noted that the opposite end member 9 has its transverse portion bent inwardly towards its pivotal end connections, and is provided with an elastic band 15, which constitutes a compression element for holding the members 1 to 9 inclusive, folded upon each other, as shown in Fig. 5. The particular manner of securing the elastic band 15 to the sides 16 of member 9, as shown in Fig. 1, may be varied. I preferably, however, employ a single elastic strip, the ends of which may be looped about sides 16, and then sewed, or otherwise suitably secured.

In mounting the device upon the hair, the members 1 to 9 inclusive, are folded in a position, as shown in Fig. 3, so that the openings 12 are in alignment to receive the strand of hair. After the device is suitably positioned upon the hair in this manner, it may be extended or spread outwardly to an extended position, as shown in Fig. 4, so that the pivotal connections 11 may thereafter be reversed to reverse the direction of the fold, as shown in dotted lines in Fig. 4. In doing so, the spaced transverse engaging portion 10 of each adjoining member is moved in the opposite direction. This causes the hair to assume a crimped condition upon the device as illustrated in Fig. 5. In order to hold the various members in this reversed folded position the band 15 may be extended circumferentially about the members as shown in this figure. By making the band of elastic material, the members may be pressed against each other with the hair wound therebetween.

The length of time required for the device shown herein to impart an artistic wave to the hair may vary in some cases. I have found that if the hair is suitably dampened before the hair is placed in the device, a wave will be formed in the hair by the time the hair is dried.

It will be noted that the essence of my invention resides chiefly in the provision of members arranged side by side, which are either provided with central openings, or which will form such openings when assembled together. By bringing the members upon each other in folded relation, these openings will be made to align with each other to receive the strand of hair to be waved. Thereafter these members may merely be reversed in order for the hair to wind about the spaced transverse hair engaging portions 10. The hair will then become suitably waved if permitted to remain on the device in this position a sufficient time. It will be noted that the elastic band 15 need not be used unless some means is desirable to temporarily hold the device in the folded

position shown in Fig. 5 on the hair. In such cases, the elastic band will not only hold the hair in such a position, but it will also tend to compress the various members against each other and upon the hair, thereby assisting in imparting an artistic permanent wave to the hair.

In Fig. 6, I have shown a modified form of my invention. Here the device is formed of loop-like members 18 pivotally connected together at 19. The transverse hair engaging portions 20 of the adjoining members 18 will be similar to the single hair engaging portion 10 of the device shown in Fig. 1. Any form of pivotal connection 19 may be used, but I preferably employ an arrangement preventing the members 18 from being displaced transversely.

In either instance, I prefer to use material of relatively small cross section, such as wire or the like, but I do not, however, intend to limit myself to this particular detail.

Without further elaboration, the foregoing will so fully explain the gist of my invention, that others may, by applying current knowledge, readily adapt the same for use under varying conditions of service, without eliminating certain features which may be properly said to constitute the essential items of novelty involved, which items are intended to be defined and secured to me by the following claims:

I claim:

1. A hair waving device comprising a plurality of members arranged side by side and foldably connected together, and adapted to receive hair through their centers when folded together, said members providing spaced transversely extending hair engaging portions which are adapted to receive the hair when said members are thereafter reversed in their folded position, and means for securing said members in folded position.

2. A hair waving device comprising a plurality of continuously connected and foldable U-shaped members, said members having their ends connecting to corners of the adjoining members and providing transversely extending hair engaging portions, and means for securing said members in folded position.

3. A hair waving device comprising a plurality of U-shaped members foldably connected together by interconnecting the ends of each member to the corners of the adjoining members, said members providing transversely connecting hair engaging portions, and means for securing said U-shaped members in folded relation with each other, said means comprising an elastic band carried by one of said members.

4. In a hair waver, the combination of a plurality of members of relatively small cross section bent substantially U-shape, the

- ends of each member connecting to the corners of the adjoining member whereby said members assume the formation of continuously connected foldable links between which and their adjacent members a strand of hair is adapted to pass for waving, and an elastic band on one of the end members for compressing said members when in folded relation upon the hair being waved.
5. In a hair waver comprising a plurality of members looped together to allow the folding thereof upon each other in two directions, said members receiving a strand of hair when folded in one direction so that when thereafter folded in the other direction said members will crimp the hair in a series of waves, and an elastic member for extending about said members for holding the same under pressure.
10. 5. In a hair waver comprising a plurality of members looped together to allow the folding thereof upon each other in two directions, said members receiving a strand of hair when folded in one direction so that when thereafter folded in the other direction said members will crimp the hair in a series of waves, and means for looping about said members when in their folded relation to compress said members and the hair therebetween.
15. 6. In a hair waver comprising a plurality of members looped together to allow the folding thereof upon each other in two directions, said members receiving a strand of hair when folded in one direction so that when folded in the other direction said members will crimp the hair in a series of waves, and means for looping about said members when in their folded relation to compress said members and the hair therebetween.
20. 7. In a hair waver comprising a plurality of members adapted to be folded upon each other so that a strand of hair may pass through the centers thereof when thus folded, means permitting said members to be thereafter extended away from each other along said strand of hair and to be again folded upon each other but in a reversed direction whereby the hair is crimped or waved, and means for holding said members in reversed folded position until the waves have been sufficiently impressed in said hair to remain therein after removing said members from the hair.
25. 8. In a hair waver comprising pivotally connected members arranged to form a series of openings and adapted to receive a strand of hair when said openings are in substantially parallel planes and to crimp the hair in a position for hair waving reversing the position of said members, and means for holding said members under pressure in

their latter position whereby the hair may thereafter be removed from said members in permanently waved condition.

9. In a hair waver comprising pivotally connected foldable members arranged to form a series of openings adapted to be in substantially parallel planes for receiving a strand of hair therethrough; when said pivotally connected members are in folded relation, the pivotal connection of said members permitting the members to be reversed in their folded relation for crimping the hair in a series of waves, and means for maintaining said pivotally connected members in reversed folded position to impart a permanent wave to the hair.

10. In a hair waver comprising pivotally connected U-shaped members arranged to form a series of openings adapted to align with each other for receiving a strand of hair when said members are folded, and then to be reversed in their alignment to crimp the hair in a series of waves when said members are reversed in their folded relation, and means for holding said members in this latter position to impart a wave to the hair.

11. A hair waver adapted to have three different positions in the waving of a strand of hair comprising a plurality of transverse members assembled in a manner to form central openings or apertures between the same, foldably connecting means permitting said members to be folded upon each other to bring said openings into substantial alignment on first and third position, said members being in unfolded condition when assuming the second position, and being reversibly foldable and passing through said second position in being folded from the first to the third positions, said members when in the first folded position adapted to receive a strand of hair through the central openings and when in the third position adapted to hold the strand of hair in a hair waving position, and means for retaining said members in said third position to impart a wave to the strand of hair.

In witness whereof, I have hereunto subscribed my name.

WILLIAM A. MEYERS.
